(57) **CLAIM**

The ornamental design for a swappable component tie as shown.

DESCRIPTION

FIG. 1 is a perspective view of a swappable component tie positioned on a shirt;

FIG. 2 is a perspective view of the swappable component tie shown with a retaining chain;

FIG. 3 is a front view of the swappable component tie;

FIG. 4 is a back view of the swappable component tie;

FIG. 5 is a top view of the swappable component tie;

FIG. 6 is a bottom view of the swappable component tie;

FIG. 7 is a left side view of the swappable component tie; and,

FIG. 8 is a right side view of the swappable component tie. The broken line outline of the shirt in FIG. 1 and the restraining chain in FIG. 2 depict environment associated with the swappable component tie, but form no part of the claimed design. The dashed broken lines along the swappable component tie depict portions of the article that form no part of the claimed design.
